UNITED STATES PATENT OFFICE.

AUGUSTUS F. HARTER, OF CHICAGO, ILLINOIS, ASSIGNOR TO CRIBBEN & SEXTON COMPANY, OF CHICAGO, ILLINOIS, A CORPORATION OF ILLINOIS.

DESIGN FOR A HEATING-STOVE.

SPECIFICATION forming part of Design No. 36,323, dated May 12, 1903.

Application filed April 10, 1903. Serial No. 152,086. Term of patent 7 years.

To all whom it may concern:

Be it known that I, AUGUSTUS F. HARTER, a citizen of the United States, residing at Chicago, in the county of Cook and State of Illinois, have invented a new, original, and ornamental Design for a Heating-Stove, of which the following is a specification, reference being had to the accompanying drawing, forming part thereof.

10 The figure is a perspective view of a heating-stove, showing my new design.

As shown in the drawing, my design consists of ribs and grooves arranged at the top of the legs to represent two reverse scrolls.

15 The base, surrounding the tops of the legs, is provided with curved ribs, while the door and the casting surrounding the door and in which it is hinged are ornamented by curved ribs

arranged to impart the appearance indicated in the drawing. The damper at the side of 20 the stove is surrounded by an ornamental plate. The top of the stove is ornamented, as shown, and is surmounted by an urn.

Having described my invention, what I claim as new, and desire to secure by Letters 25 Patent, is—

The ornamental design for a heating-stove, as herein shown and described.

In witness whereof I have hereunto subscribed my name in the presence of two sub- 30 scribing witnesses.

AUGUSTUS F. HARTER.

In presence of—

PETER BAUM,
W. A. SMITH.
